UNITED STATES PATENT OFFICE

106,904

DESIGN FOR A CRIB-FAN

Candido M. Ramos, Delano, Calif.

Application July 28, 1937, Serial No. 70,707

Term of patent 7 years

To all whom it may concern:

Be it known that I, Candido M. Ramos, a citizen of the Philippine Islands, residing at Delano, county of Kern, and State of California, have invented a new, original, and ornamental Design for a Crib-Fan, of which the following is a specification, reference being had to the accompanying drawing forming a part therein, wherein:

I claim:—

The ornamental design for a crib-fan, as shown.

CANDIDO M. RAMOS.
